DESIGN.

—o—
J. S. VAN BUREN.
HEATING STOVE.

No. 18,773.

Patented Nov. 27, 1888.

UNITED STATES PATENT OFFICE.

JAFEW S. VAN BUREN, OF ALBANY, NEW YORK, ASSIGNOR TO RATHBONE, SARD & CO., OF SAME PLACE.

DESIGN FOR A HEATING-STOVE.

SPECIFICATION forming part of Design No. 18,773, dated November 27, 1888.

Application filed June 29, 1888. Serial No. 258,576. Term of patent 3½ years.

To all whom it may concern:

Be it known that I, JAFEW S. VAN BUREN, of Albany, in the county of Albany and State of New York, have invented a certain new and useful Design for Stoves; and I do hereby declare the following to be a full, clear, and exact description of the invention, such as will enable others skilled in the art to which it pertains to make and use it, reference being had to the accompanying drawing, which forms part of this specification.

My invention relates to an improvement in designs for heating-stoves; and it consists in the ornamental configurations and shapes, which will be more fully described hereinafter, whereby a very ornamental stove is produced; and the object of my invention is to produce a stove which is highly ornamental and pleasing to the eye. The accompanying photographic illustration represents a stove which embodies my invention.

A represents the base, which is rectangular in shape, and which is supported upon four legs, B, having an outline ogee in form. Placed between the legs B are the four connecting-strips, C, which have raised ornamental scroll-work upon their surfaces. At the center of each plate C there is a circle formed, which contains a number of parallel beads, and from which radiate four small scrolls. Upon the sides of this central circle are large scrolls, as shown. The ends of these strips are circular, corresponding to the volutes formed upon the legs B. The columns D at each front corner of the stove form the outer walls of the air-circulating flue, open at top and bottom, and have their surfaces ornamented with conventional foliage.

The side panels, E, of the stove are each ornamented by a sprite holding aloft a flaming torch, the flame of which passes through the damper F and extends on up to the top of the panel.

The front of the stove has the panel G extending across its surface and projecting forward several inches. This panel G has openings and is ornamented with spiral beads, which extend in opposite directions each side of the center. The ash-door H, which is just below this panel G, has irregular-shaped damper-openings surrounded by ornamented

beads and scrolls terminating at each end with conventionalized palm-leaves. Above the panel G are the two mica doors I, each one of which has two openings, and have ornamental scrolls running through the central bar in front of the mica. Above the mica doors I is a bead, J, which has the same curve as the panel G. Above this bead J are the two upper mica doors, L, which are each divided by two cross-bars into four spaces to receive the mica, and are ornamented by scrolls springing from the center bars, and, turning outward, are finished with smaller scrolls at the corners of the doors. Above these doors is an ornamental plate, N, which has a face at its center and upon each side thereof a rosette surrounded upon three sides with ornamental scroll-work.

The top O of the stove is composed of two convex moldings, and the upper one is ornamented with small parallel beads, which extend vertically.

The top of the stove P is ornamented with heavy scroll-work and open or fret work at the top of each one of the flues D. The cover Q has an ornamental scroll-work panel at the front and sides, and forms the seat for the top ornament, R.

Extending from opposite sides of the stove, near its lower portion, are the ornamental brackets S, between which the foot rests T are supported. These foot-rails are made semi-cylindrical and provided at each end with an ornamental hemispherical cap, U.

As will be seen from the accompanying photographic illustration, this stove is very highly finished and presents an elegant and beautiful appearance, which especially adapts it for use in parlors, sitting-rooms, and other similar places.

Having thus described my invention, I claim—

1. In a design for a heating-stove herein described and shown, the base A, consisting of the feet B and the ornamental skirting C, as shown.

2. In a design for a heating-stove herein described and shown, the ash-door H, having irregular damper-openings and surrounded by ornamental beads and scrolls terminating at each end with palm-leaves, as described.

3. In a design for heating-stoves herein

shown and described, the fire-door L, divided by two cross-bars into four spaces and ornamented by scrolls springing from the center bars and turning outward, finishing with small scrolls at the corners of the door, as shown.

4. In a design for a heating-stove herein described and shown, the top consisting of the convex molding O and convex ornamental molding P, having the ornamentation and shape shown.

5. In a design for a heating-stove herein described and shown, the body consisting of the ash-door H, panel G, mica doors I, fire-doors L, the top O P Q, the brackets U, and

the foot-rest T, all having the shape or ornamentation shown.

6. In a design for a heating-stove herein described and shown, the cover Q, consisting of an ornamental scroll-work panel at each side and surrounded by ornament R, as set forth.

In testimony whereof I affix my signature in presence of two witnesses.

JAFEW S. VAN BUREN.
